UNITED STATES PATENT OFFICE.

EDWIN M. GOLDSMITH, OF PHILADELPHIA, PENNSYLVANIA, ASSIGNOR TO FRIED-
BERGER-AARON MANUFACTURING COMPANY, OF PHILADELPHIA, PENNSYL-
VANIA, A CORPORATION OF PENNSYLVANIA.

DOLL.

1,370,107.

Specification of Letters Patent.

Patented Mar. 1, 1921.

Application filed April 7, 1919. Serial No. 288,216.

To all whom it may concern:

Be it known that I, EDWIN M. GOLDSMITH, a citizen of the United States, residing at Philadelphia, county of Philadelphia, and State of Pennsylvania, have invented a new and useful Improvement in Dolls, of which the following is a full, clear, and exact description, reference being had to the accompanying drawings, which form a part of this specification.

The object of my invention is to provide a stuffed doll that will be readily washable. Dolls of this character comprise ordinarily a cover stuffed with cotton or other suitable filling; the facial features of the doll, and perhaps also a representation of garments, being printed, or possibly woven, on the outside of the cover. Animal dolls are also made in the same way. These dolls are especially desirable for babies and younger children. They are soft, yielding and unbreakable and relatively inexpensive. They are, however, decidedly objectionable in that they are not washable. If their washing should be attempted, the moisture would soak through the filling, which would become soggy and practically undriable. Naturally, these dolls become dirty very quickly, and in view of the propensity of the very young to chew or suck playthings, the careful parent must soon remove the doll from the child. Usually it is discarded or thrown away before it exhibits any other serious indication of wear than the superficial dirt with which it is coated.

It is clear that if dolls of this character could be made washable, they would become substantially imperishable and could always be put into fit condition for use by the child. My invention involves such modification of structure as will provide a doll having the same desirable characteristics above described, but which is washable an indefinite number of times, thereby providing a doll which will even outlast the childhood of the owner and which may be kept at all times in a clean and sanitary condition.

In making my improved doll I provide a body comprising a cover and interior filling material. Such a body is shaped to

conform to the desired finished product and may be said to be practically the same as an ordinary finished doll of the popular type except that, superficially, it is devoid of any markings representing features, dress, or the like. Surrounding this body is a removable shell, skin or envelop having imprinted on its outer surface the features of the doll and also, if desired, comprising representations of other parts of the body and an actual garment or representation thereof. The outer envelop may be of bag form having a closure at one end; or it may be split longitudinally and fastened along the opening. The outer envelop should be so shaped and fastened that it may be readily unfastened and removed. It may be made of any suitable material, such as a knitted or woven fabric; or it may be made in part of one material and in part of another, as, for example, a textile material having a celluloid face.

When the doll becomes soiled, the exterior envelop may be unfastened, slipped off, washed, dried, replaced and refastened, and the doll will be as good and clean as if new.

In the drawings, which show embodiments of my invention:

Figure 1 is a front view of the body of the doll; Fig. 2 is a front view, and Fig. 3 a rear view, of the completed doll; Fig. 4 is a front view of the body of another doll; Fig. 5 is a front view, and Fig. 6 a side view, of the completed doll.

The body of the doll comprises an inside cover *a* filled with cotton or other soft filling *b*. The outside envelop *c* of the doll of Figs. 2 and 3 comprises a garment and a representation of the face of the doll. It is of a bag shape, being open at *d* near its lower end and at the rear. The overlapping edges of the outer envelop may be secured together in any convenient way, as by snap fasteners.

The doll of Figs. 4, 5 and 6 comprises a body *e* and an outside envelop *f*. The envelop *f* is shown slit longitudinally at *g*, the overlapping edges being fastened together as desired. The envelop *f* has formed upon its outer surface only the representa-

tion of the face of the doll, and the user may have one or more doll dresses which may be put on and taken off as desired.

Of course the inside cover of the doll 5 need not be blank, but any superficial markings or representations thereon would be functionless.

I am aware that it is old to form an animal doll with a removable and replaceable cover containing appendages that impart to the doll the aspects of an animal, but these appendages soon become detached, leaving an unlielike doll. In my invention, the removable envelop has the features of the doll, and, as in Figs. 1, 2 and 15 3, other aspects of the doll, superficially applied thereto, as by printing, stitching or embroidery, so that there are no detachable parts, making the doll practically inde- 20 structible.

Having now fully described my inven-

tion, what I claim and desire to protect by Letters Patent is:—

A doll comprising a covered stuffed body contracted relatively near one end to form 25 a head and trunk and provided at the free end of the trunk portion with a pair of projections simulating feet, an outer removable and replaceable envelop fitting the entire body and devoid of appendages and 30 provided with superficial markings exhibiting the aspects of a human doll, said envelop being slit in the body portion between its ends, the arrangement being such that the envelop will be retained in position by engagement of the envelop on the head and feet, and means for closing the slit in the envelop.

In testimony of which invention, I have hereunto set my hand, at Philadelphia, Pa., 40 on this 4th day of April, 1919.

EDWIN M. GOLDSMITH.
